UNITED STATES PATENT OFFICE.

SAMUEL B. McHENRY, OF BLOOMSBURG, PENNSYLVANIA.

BROOM-MANUFACTURING MACHINE.

1,306,307.

Specification of Letters Patent. Patented June 10, 1919.

Application filed March 13, 1916. Serial No. 83,915.

To all whom it may concern:

Be it known that I, SAMUEL B. McHENRY, a citizen of the United States, residing at Bloomsburg, in the county of Columbia and State of Pennsylvania, have invented certain new and useful Improvements in Broom-Manufacturing Machines; and I do declare the following to be a full, clear, exact description of the invention, such as will enable others skilled in the art to which it appertains to make and use the same, reference being had to the accompanying drawings, and to the letters and figures of reference marked thereon, which form a part of this specification.

This invention relates to improvements in machines for manufacturing or making brooms.

The invention has for its object, among other things, to provide for readily and firmly holding the broom-forming material during the process of manufacture.

A further object of the invention is to provide for rapidly and effectively forming a desirable and substantial broom.

A still further object of the invention is to provide for adapting the machine for ready adjustment for making brooms of various sizes.

With these and other objects in view, the invention consists of certain instrumentalities and features of construction substantially as hereinafter more fully disclosed and defined by the appended claims.

In the accompanying drawings is illustrated the preferred embodiment of my invention wherein it will be understood that various changes and modifications as to the detailed construction and arrangement of parts may be made without departing from the spirit or scope of the claims and in which drawings—

Figure 1 is a plan view of my invention, the same being in inoperative positon.

Fig. 2 is a sectional elevation thereof taken on line 2—2 of Fig. 1, with one of the brush-block holding members or jaws also shown in dotted line position, together with said brush-block and broom-material looping member, as when securing the brush-material to said block or broom-head.

Fig. 3 is a horizontal detailed sectional view of the complete article or broom.

Fig. 4 is a sectional elevation of the device, with the parts in position as when the

broom-material looping member is initially disposed for looping said broom-material.

Fig. 5 is also a like sectional view of the same parts, as when the broom-material looping operation has been effected and before the "boxing," as it were, of said broom-material upon the block or broom-head has been, and is about ready to be performed.

Fig. 6 is a transverse vertical section taken through Fig. 5, on line 6—6.

In carrying out my invention, I suitably mount the several operative parts thereof upon a general frame 1. Alining shafts 2, 2', having their opposed ends suitably spaced apart for a purpose presently seen, are equipped at said ends with jaws 4 and 5, respectively, of preferably oblong or rectangular form, one having a recessed face, said jaws being adapted to receive therebetween, and provide for the holding of the broom-material holding block or head 24. One of these shafts 2 has suitably secured thereon a block or bracket 8, a short distance from its jaw-equipped end, which serves for temporarily holding what may be termed a looping device 9, the operation and function of which will later be explained. A gage 7, of suitable adaptation for use in regulating or truing the lengths of the strands of the broom-material, is suitably secured upon the same shaft 2.

Upon one end of the shaft is freely mounted a preferably U-shaped plate or yoke 13, it being let into an annular reduction of said shaft and held in place by a nut applied to said end of the shaft. Fulcrumed upon the supporting frame and having its lower end pivoted to the yoke or plate 13 is a weighted lever 10, for bringing the brush-material-holding block-jaws 4, 5 together or rather in engagement with said block. The weighting of said lever is effected preferably by suspending therefrom a weight 12 by means of a chain 11 with its ends secured to said lever and weight, respectively, with the chain initially resting upon the lever, the weight, however, freely depending therefrom, as shown, thus providing for the retention of the lever in either of its positions under pressure or against casual movement, as is obvious.

Two clamping members 14 and 15 are oppositely positioned to each other, above and below the broom-material-holding block within its engaging jaws, respectively, each

- being preferably of bail-like form, with its arms suitably pivoted to preferably upwardly and downwardly projecting portions of the supporting frame at their extreme 5 rear ends. Said clamping members 14, 15 are pivotally connected to levers 16 and 17, and the levers 16 and 17 are pivotally connected by links 22 and 23 to an upright 21 secured to a transverse beam 6. Said levers 10 16 and 17 are also connected preferably by chains 19 to the supporting frame and preferably by helical springs 18 to the shaft 2. The springs 18 are provided for holding the clamp-members 14 and 15 out of action 15 when the broom-material is being positioned upon the block 24. Chains 19 serve to retain the levers 16 and 17 in effective position when said levers pass forwardly of the perpendicular, particularly as seen in Fig. 4.
- 20 Pairs of rods or members 20 are carried by the beam 6 and have connected thereto an operating bail-like lever 29, in turn linked as at 30 to supports 31 suitably secured in position, all as seen particularly in Fig. 1.
- 25 These rods or members 20 are provided at their forward ends, in the upper surfaces, with notches or recesses to receive the brush-material-looping devices 9, the latter, however, as previously stated, being temporarily 30 disposed upon the block or bracket 8 on the shaft 2, until called for in effecting the looping operation.
- When the jaws 4, 5 have been moved so as to grip or clamp the broom-material-holding-block 24 in position, as seen in Figs. 4 and 5, which is effected by moving the lever 10 into the dotted line position, indicated in Fig. 2, (the broom-material having been suitably gaged and placed upon said block) 40 the lever 29 is suitably actuated or moved into the position indicated in Fig. 5. The looping device 9, it will be seen, will have engaged and looped or doubled the broom-material strands upon themselves, this also 45 being disclosed by Fig. 6. The looping device 9 is now withdrawn and again disposed upon the block 8, and by suitably manipulating the lever 29, the clamping members 14 and 15 are brought in clamped position upon 50 the broom-material as seen in Fig. 4, for tightly or firmly holding the broom material upon the block 24, the clamping members 14, 15 being thus retained until the broom material has been wired as at 26 down 55 upon the block and a metallic cap 28 has been suitably nailed or secured over the looped and wired end of the broom material, as by stapling as at 27, all as shown particularly in Fig. 3. Now by suitably actuating the lever 29 the clamping members 60 14, 15 are withdrawn, and by suitably actuating the lever 10 the block-clamping jaws 4, 5 are released from said block, permitting the resultant broom-forming member, with 65 its attached head, to be removed. It will

be noted that the lower clamping member 15 has an approximately U form, the lateral upwardly extending portions thereof serving, as previously indicated, to effect the "boxing" as it were, of the broom material 70 and thus provide for compactly holding it in place.

In operation, the broom material, designated as 25, is applied to extend longitudinally along opposite surfaces of the head or 75 block 8 and of the prospective broom head or block 24, with the inwardly disposing of the inner end of the broom material defined by the gage 7 and whereby may be gaged the broom material for making the same of different or required lengths. Now by moving the lever 29 to the left, as in Fig. 4, the clamping members 14, 15 are caused to effectively engage and hold the broom material upon the block 24, the members or arms 20 80 being carried simultaneously in the same direction as the members 14, 15 and positioned as in said figure. The broom material is now wired down, as at 26, upon the block 24, and staples driven through the wire into 90 said block. The lever 10 is next moved into the dotted line position, as in Fig. 2, providing for carrying the head 8, with the loop 9, into the dotted line position of said figure, whereby the shaft 2 will be longitudinally 95 moved, providing for clamping the block or head 24 between the jaws 4 and 5, and so actuating the member 9 as to cause it to fold the brush material upon itself, as seen in Figs. 5 and 6, the lever 29 having been previously moved into initial position as indicated in the same figure and Fig. 2. Simultaneously with this latter manipulation of parts, as in the movement of the lever 10, the member 9 will be moved into locked engagement with the arms of the member 20, as seen in Fig. 6, providing for the holding 100 of the broom material in position for the application thereto of the cap 28. Preliminary, however, to applying the cap, the lever 10 is moved into initial or full-line position, as seen in Fig. 2, taking the jaw 4 and the member 8, with the looping member 9 removed to the latter, out of the way for the application of the cap. The latter is now 105 suitably secured over the inner or butt end of the broom, thus far completed by suitably nailing it to the head or block 24, thus completing the brush-forming operation. It will be understood that in nailing the cap 110 and wiring the broom material upon the head or block 24 the shaft 2 is capable of being readily turned or revolved manually for conveniently performing said nailing and wiring operations.

I claim:

1. A broom making machine, including aligned shafts equipped with jaws adapted to receive therebetween and engage a broom-head-forming member, means adapted to 130

longitudinally move one of said shafts, a looping device carried by the other of said shafts, adapted to engage the broom-material, and means associated therewith for causing said looping device to effect the looping or doubling of said broom-material upon itself.

2. A broom-making machine, including alined shafts equipped with jaws adapted 10 to receive therebetween and engage a broom-head-forming member, one shaft being longitudinally slidale, the other shaft having associated therewith a looping device, longitudinal members adapted to carry said 15 looping device, and means for causing said looping-device carrying means to engage and loop the broom-material.

3. A broom-making machine, including alined shafts equipped with jaws adapted 20 to receive therebetween and engage a broom-head-forming member, one of said shafts being movable longitudinally, means associated with said shaft to provide for imparting such movement to said shaft comprising a lever having a swiveled-connection 25 with said shaft and having means for automatically retaining the same in either of two positions against movement, longitudinal members associated with the other shaft 30 and carrying a looping device for engaging the broom-material and looping it upon itself, clamping members arranged for holding the looped broom-material while being secured upon the broom-head-forming member, and means for actuating said clamping members.

4. A broom-making machine, including alined shafts equipped with jaws adapted 40 to receive therebetween and engage said broom-head member, means for moving one

of said shafts longitudinally, longitudinal members carrying a looping device for effecting the looping of the broom-material, a lever for actuating the longitudinal members carrying the looping device, linked to 45 a fixture, said longitudinal members being connected to said lever, clamping members adapted to engage and hold the broom-material upon said broom-head, one of said clamping members being formed to operate 50 with the opposite clamping member and to provide for "boxing" the broom-material.

5. A broom-making machine, including alined shafts equipped with jaws adapted 55 to receive therebetween the broom head member, means for moving one of said shafts longitudinally, means carrying a looping device for looping the broom-material upon itself, associated with the other 60 shaft, an actuating lever for said looping device, clamping members for engaging said broom-material in holding it upon said broom-head member when securing the broom-material thereto, additional levers 65 connected to said clamping members, links between said additional levers and fixed members, springs between said additional levers and a fixed member, and means to retain said additional levers in effective position when said levers pass beyond the perpendicular.

In testimony whereof I have signed this specification in the presence of two witnesses.

SAMUEL B. McHENRY.
